(57) **CLAIM**

The ornamental design for a display screen or portion thereof with a baccarat game graphical user interface, as shown and described.

DESCRIPTION

The FIGURE is a front elevation view of a display screen or portion thereof with a baccarat game graphical user interface showing our new design.

The heavier broken lines in the drawing illustrate the display screen or portion thereof, while all other broken lines illustrate portions of the baccarat game graphical user interface. None of the subject matter shown in broken lines forms part of the claimed design.
